(57) **CLAIM**

The ornamental design for a set of electronic display screens for gaming machines as shown and described.

DESCRIPTION

FIG. 1 is a perspective view of the set of electronic display screens for gaming machines.

FIG. 2 is a front elevational view thereof, the rear elevation view being a mirror-image of the front elevation view.

FIG. 3 is a left side elevational view thereof, the right side elevation view being a mirror-image of the left side elevation view; and,

FIG. 4 is a top plan view thereof.

The broken lines in the drawings depict portions of the set of electronic display screens for gaming machines that form no part of the claimed design.

1 Claim, 4 Drawing Sheets
